(57) **CLAIM**

The ornamental design for an ornamental tag, as shown.

DESCRIPTION

FIG. 1 is a perspective view of an ornamental tag showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of an ornamental tag;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is a perspective view of a third embodiment of an ornamental tag;

FIG. 16 is a front view thereof;

FIG. 17 is a rear view thereof;

FIG. 18 is a left side view thereof;

FIG. 19 is a right side view thereof;

FIG. 20 is a top view thereof;

FIG. 21 is a bottom view thereof;

FIG. 22 is a perspective view of a fourth embodiment of an ornamental tag;

FIG. 23 is a front view thereof;

FIG. 24 is a rear view thereof;

FIG. 25 is a left side view thereof;

FIG. 26 is a right side view thereof;

FIG. 27 is a top view thereof;

FIG. 28 is a bottom view thereof;

FIG. 29 is a perspective view of a fifth embodiment of an ornamental tag;

FIG. 30 is a front view thereof;

FIG. 31 is a rear view thereof;

(Continued)

FIG. 32 is a left side view thereof;

FIG. 33 is a right side view thereof;

FIG. 34 is a top view thereof; and,

FIG. 35 is a bottom view thereof.

The broken lines showing a chain and jump ring represent environment and the remaining broken lines in the drawings represent portions of the ornamental tag which form no part of the claimed design.

1 Claim, 25 Drawing Sheets
